1,611,005

UNITED STATES PATENT OFFICE.

MACDOUGALD DEXTER, OF COLUMBUS, GEORGIA, ASSIGNOR TO DEXTER VENTILATOR COMPANY, A CORPORATION OF GEORGIA.

VENTILATOR.

Application filed October 25, 1924. Serial No. 745,847.

My invention relates to ventilators, and particularly to roof ventilators wherein it is desired, at the least possible expense and without detraction from the architectural effect of a building, to afford the maximum controllable ventilation and at the same time complete protection against access of rain or water through the ventilator into the building.

More particularly, my invention contemplates a novel and effective arrangement of baffles relative to a roof opening which are so disposed relative to such opening and to each other that direct access of rain or water is prevented while the outflow of air is obstructed to as small an extent as is possible.

It is a further advantage of my improved ventilator that the baffles are so arranged as to be unaffected by the action of wind except in so far as it may be desirable to utilize the wind action to accelerate the outflow of air through the ventilator by an aspirating effect auxiliary to the natural draft induced by the heat within the ventilated compartment.

My invention is especially concerned with the design and construction of the ventilators to be applied to the ridges or high points of roofs or associated with the parapet walls at the high points of flat pitch roofs, such ventilators being designed to conceal from view the presence of the ventilating opening through the roof and to conform to the ridge or roof treatment so as not to attract notice.

My invention further contemplates the combination with one baffle rising from each pitch of the roof and partly overhanging an underbaffle disposed to shed the rain from the ventilating opening. In my preferred arrangement the baffles slope in the same direction as the roof they overhang, and the outer baffle or baffles are spaced from the roof opening and the underbaffle so as not to restrict the rising outflow of air through the ventilator. The objects of my invention are attained when the inner and outer baffles, correlated as above described, are so mounted on the roof as to prevent the free access of air currents along the roof to the space between the baffles.

My invention further contemplates the arranging of the outer baffle or baffles with outlet ports provided between the bottom edge thereof and the roof so that the water shed from the underbaffle may drain off and

such wind that makes its way through the restricted drain ports will not interfere with the contemplated functioning of the ventilator, nor will it be of sufficient volume and force to blow any of the water, seeking to escape through the drain ports, into the roof opening. However, in ordinary practice, these openings are merely of such size as to drain the ventilator, the main aspirating effect being obtained from the concurrent flow of the deflected wind with the air current or currents as they escape from the ventilator.

My invention further comprises the novel details of construction and arrangements of parts, which are hereinafter more particularly described and claimed, their preferred embodiments only being illustrated in the accompanying drawings which form a part of this specification, and in which:

Fig. 1 is a perspective view through a ridge ventilator employing curved baffles and showing the damper in open position.

Fig. 2 is a partial longitudinal cross-sectional view through the ventilator shown in Fig. 1, the full lines showing the damper in open position and the dotted lines showing it in closed position.

Fig. 3 illustrates a modified method of connecting the ventilator to the roof.

Fig. 4 is a cross-sectional view illustrating my ventilator in a single type form utilizing flat baffles and associated with the parapet wall to illustrate its use on a flat single pitch roof.

Similar reference numerals refer to similar parts throughout the drawings.

Heretofore in designing ventilators, and particularly roof ventilators, the walls or baffles of the ventilator have been so disposed and arranged as not only to impede the outward flow of hot air from the compartment to be ventilated, but in many cases to have this flow directly opposed to and in effect stopped by the action of wind. This is particularly true in the few attempts that have been made to produce ventilators of the ridge type which utilize a roof outlet opening of large cross-sectional area and of considerable extent, and for this reason and perhaps also for the reason that practical means for regulating and closing such large ventilators have not been perfected, the same have not come into general commercial use. In my ventilator I have sought to adhere to the greatest simplicity in design to the

end that it might be readily fabricated anywhere, easily and cheaply applied, and regulated by simple and inexpensive means which will accurately control the rate of air discharge to that desired for the correct ventilation of the interior of the building.

With these objects in view, I have illustrated in Figs. 1 and 2 my ridge type ventilator. Here I show the roof comprising rafters 1 and sheathing 2, the latter being stopped short of the ridge so as to leave a ventilating opening 3 having the width and length desired for the proper ventilation of the interior of the compartment to be ventilated. The ends of the rafters abut and are nailed together in accordance with the existing practice, or where ridge plate is used this is cut down between rafters so as not to impede the passage of air to the ventilator. The object of my ventilator is to protect such ridge opening from rain or wind while permitting the free exhaust of air from the compartment below. To this end I provide on each side of and parallel with the ridge opening an outer baffle 4 which is preferably of ogee shape in cross section and is mounted on the roof by means of brackets disposed at spaced intervals and having spaced upper legs riveted or spot welded to the upper edge of the outer baffles and their lower legs 5 bent down in opposite directions and underlying the bottom edge of the baffles which edge is adapted to be riveted, bolted, or suitably connected thereto. In the preferred arrangement of my baffle shown in Fig. 1, I connect each lower leg 5 of the bracket to a stamped-down portion 6 along the lower edge of its respective baffle, such edge between these stamped-down portions being thereby held slightly raised above the roof covering 7 to provide drain outlets 8 for the water falling in the ventilator. If desired the lower legs 5 of the brackets may rest upon a flashing strip 9 extending the length of the ventilator and preferably beyond the lower edge thereof, the upper edge of the flashing being upturned at 10 to stiffen the plate, assist in maintaining alignment in the ventilator, and to prevent the possibility of wind driving water falling on the flashing upwardly over its edge. The lower edge of the flashing is bent down slightly to cause it to hug the roof tightly. The bracket which may be of any suitable character is shown comprising legs 11 bent at right angles to the legs 5 and connected at their upper ends by an angled cross member 12. This serves to cross brace the brackets and to hold the baffles 4 in proper spaced relation. The upper edge of each baffle 4 is bent back under upon itself to form a pocket 13 extending its full length and adapted to stiffen that edge of the baffle. This pocket receives at intervals the upper bracket legs 14 which are

riveted, spot welded or bolted thereto and to the cross bracket number 12. Before riveting the bracket elements together, the ridge roll 15 of the roof, which forming the inner baffle and is preferably in the form of an inverted V-shaped member, is mounted on cross members 12 of the brackets and has its lower edges interposed between the bracket members 12 and 14 and connected rigidly in place by the rivets or bolts which assemble said members. This gives a very simple, inexpensive yet rigid structure.

It will be observed that the peak of the ridge roll 15 rises substantially above the upper edge of the baffles 4 and that each side of its base is spaced approximately the same distance from the adjacent baffle 4 that it is spaced from the adjacent side edge of the roof opening. By this arrangement the air has a passage of approximately constant minimum cross sectional area through which it flows in rounding the lower edges of the ridge roll and thus I provide a minimum of obstruction to the free outflow of air. It is to be observed that each lower edge of the ridge roll or inner baffle projects substantially beyond a vertical plane through the adjacent side of the roof opening, this arrangement having for its object to protect the opening against direct access thereto of rain. Each lower edge of the ridge roll also projects substantially beyond a plane connecting the upper edge of the adjacent wind baffle 4 and the adjacent side of the roof opening. However, the upper edge of the wind baffle 4 does not necessarily overhang the roof opening, it being only necessary that the ridge roll shall in conjunction with the baffles 4 prevent the possibility of wind driven slanting rain gaining access to the roof opening.

In the operation of my ventilator as thus described, the warm air from the compartment to be ventilated rises naturally to the ridge of the roof and thence flows freely out through the large roof opening. As it escapes from the opening it is divided and flows in opposite directions as currents which round the edges of the ridge roll and pass upwardly along the ridge and escape to the atmosphere. This provides a free escape for air with a minimum obstruction or friction from the passages and without any reverse flow or downward deflection, and moreover when wind is blowing it will be deflected upwardly by the pitch of the roof and by the baffle 4 so that it will flow over the top edge of the baffle 4 in a direction concurrent with the outflow of air from the ventilator and it will thus act with an aspirating effect on the ventilator. Moreover, due to the design and position of the ridge roll, the wind blowing from either side will ride over the lee side of the ridge roll in such way as to aspirate the outflow of air from

that side also and thus the ventilator is of the true aspirating type, regardless of the direction of wind flow. All rain or water falling through the openings between the ridge roll and the baffles 4 will flow downwardly over the bottom edges of the ridge roll and will drop upon the flashing or roof and will pass freely out through the openings 8 between the depressed portions in the lower edge of the baffles. This water will not collect in the ventilator and roof deterioration will not result.

Where it is desired to provide damper means to control the outflow of air through the ventilator, I provide an elongated damper 15^a formed of a strip of metal suitably stiffened by the provision of a center ridge 16 and provided at intervals with eye bolts 17 suitably connected by links 18 which swing from the ridge roll overhead and are of such length as to permit the damper when lowered to close the roof opening. In order to adjust the damper I connect to it near one end thereof a pull cord or chain 19 which is adapted to pull the damper longitudinally and thus swing it on its supports which, being fixed overhead, will cause the damper to rise as it is moved longitudinally. In this very simple manner the outflow of air through the roof opening can be regulated. As shown the pull cord passes over a pulley 20 at one end of the roof opening which is overhung by the raised damper and I preferably provide at least one fusible link 21 in the pull cord which will fuse under abnormal temperatures and permit the damper to drop automatically by gravity to close the ventilating opening and thus prevent draft which would accelerate a conflagration. Where a long ridge ventilator is provided it is desirable to extend the cord for the greater portion of its length so that the fusible links therein will more readily respond to local conditions. The ventilator has suitable end closures 22.

In Fig. 3 I show a means to avoid driving in nails or fastenings through the roofing material which is especially desirable where the ventilator is to be applied to slate, metal or tile roofs. Here wire fastenings 23 are passed around the brackets and drawn down through holes 31 in the flange 10 into the ventilator opening and secured to nails or the like 24 in the underside of the decking or sheathing.

In Fig. 4 I show the embodiment of my invention as a parapet ventilator for a single pitch roof 25 which at its high edge adjoins the parapet 26. Here I provide the ventilator opening 27 between the decking and parapet which is interrupted only by the rafters. Extending parallel with the parapet and rising at an easy angle from the roof at a point spaced from the opening 27 is the outer baffle 28 which in this embodi-

ment is shown flat but which obviously may be curved as in Fig. 1. This baffle at its lower edge is provided with indented portions receiving fastenings to attach it to the roof. Its upper edge is bent back to form the pocket and receive the upper ends of the brackets 29, which are mounted on lower brackets 30 attached to the roof. An inner baffle 31 is provided which is connected along its upper edge in any suitable manner to the parapet and has its lower edge interposed between the brackets 29 and 30 and held in place by their assembly rivets or bolts. This inner baffle is shown flat and inclined substantially parallel with the outer baffle. If curved baffles are used both would have a corresponding curvature.

The ventilator thus described in effect constitutes one-half of the ventilator as described in Fig. 1, inasmuch as each side of that ventilator really functions independently of the other, except in that some protection must be provided on the opposite side of the roof opening from the baffle 4 to take the place of the parapet in Fig. 4. Obviously a damper could be arranged for the parapet ventilator in the same manner as described in Fig. 2. The operation of this ventilator is the same as that already described in that the air currents from the compartment ventilated will rise continually and pass with an unobstructed and unrestricted flow through an angle of approximately 180° about the lower edge of the inner baffle and hence escape to the atmosphere. The wind deflected up the outer baffle will flow concurrently with the outflowing ventilation current and the wind deflected over the parapet from the opposite direction will pass over the ventilator also with aspirating effect so that the ventilator will function in all respects substantially as that described in Fig. 1.

Obviously my improved type of ventilator lends itself readily to be harmoniously blended into architectural effects and adapted to any capacity desired, from the ventilation of a small house to that of large industrial buildings, and it can take the place of ridge roll or a deck mold, or co-operate with a parapet wall. When I refer to a ventilator as associated with a roof I mean to include any portion of the covering of a structure. It is obvious that the roof 7, or the flashing strip 9, or both together, as shown, may have any pitch from the almost horizontal type used on the flat roof shown in Figure 4 through various intermediate angles of roof pitch to a substantially vertical type, such as would occur in a saw tooth roof. Moreover, when I refer to the baffle (4 or 28) as "rising from the roof," I mean merely to state that the outer baffle elements shall be so related to the roof that substantially none of the air currents passing along the

roof can gain free access to the space within the ventilator. In other words, the outer baffle will rise from the roof when so connected therewith, either directly or indirectly, as to prevent air currents gaining access to the space within the ventilator except to a negligible extent through the restricted drainage ports provided to carry off the rain water that would otherwise collect in the ventilator and overflow into the roof opening.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A ventilator comprising, in combination, a roof having a ventilating opening therethrough, an outer baffle inclined correspondingly with the inclination of the underlying portion of the roof and rising from the roof at a point spaced substantially from the adjacent side of the roof opening, and an inner baffle interposed between the outer baffle and the roof opening, which inner baffle is inclined to dispose its lower edge in position to overhang the adjacent side of the opening between the latter and the top of the first mentioned baffle, means for the escape of water falling between the baffles, and means on the side of the opening opposite the first mentioned baffle to deflect wind over the ventilator.

2. A ventilating cover for a roof aperture comprising an inclined baffle rising from the roof on each side of the roof aperture and inclined to correspond to the inclination of the roof underlying it and rising from said roof at a substantial distance from the roof aperture, in combination with a ridge roll interposed between the upper edges of said baffle and having its lower edges overhanging the sides of the roof aperture.

3. A ventilator for a roof ridge having an aperture extending along the ridge, comprising a ridge roll raised above said aperture to provide lateral outlets for the ventilating currents and to cover said aperture against the direct access of rain, and inclined baffles spaced from and flanking the ridge roll and adapted to intercept access of rain laterally into said aperture and to deflect wind from passing under the ridge roll, there being outlets provided for the escape of water falling between the baffles.

4. A ventilating means according to claim 3, in which said flanking baffles rise from the roof at points substantially spaced from the ventilating aperture and leave an

unrestricted passage for the outflow of air currents around the lower edges of the ridge roll.

5. A ventilating cover for a roof aperture, comprising an inclined cover above the aperture which overhangs a side of same, a similarly inclined baffle rising from the roof and extending to a point beyond a plane through the adjacent edges of the opening and cover, in combination with means on the opposite side of said aperture from said baffle to deflect the wind over the ventilator and means for the escape of water falling on the cover.

6. A ventilating cover for a roof aperture, comprising a cover overhanging the sides of the opening and substantially spaced therefrom, and oppositely inclined baffles rising from the roof and each having its upper edge disposed outside of and above the adjacent edge of the cover and extending beyond an inclined plane passing through the adjacent edges of the aperture and cover.

7. A ventilating means of the character described in claim 6, in combination with transverse braces adapted to support the cover and upper edges of the inclined baffles.

8. A ventilating means of the character described in claim 6, in combination with means to support the baffles with part of their lower edges raised slightly above the roof for the purposes described.

9. A ventilating means in accordance with claim 6, including a transverse bracket means to brace and support the cover, and means to support the inclined baffles on said bracket.

10. A ventilating means of the character described in claim 5, in combination with an upturned flashing extending along the side of the aperture that is overhung by the baffle.

11. A ventilating cover for a roof aperture comprising associated baffles disposed to intercept the access of rain while providing a circuitous constantly rising outlet passage for the ventilating air current, in combination with a damper having swinging supports and adapted when lowered to close the roof aperture, and means to swing said damper endwise on its supports to regulate the rate of outflow of the air current, substantially as described.

12. A ventilating means of the character described in claim 11, in which the aperture is disposed in, and extends substantially co-extensive with, the roof ridge, and in which the means to swing the damper includes an overhead pull connection extending lengthwise of the damper and comprising a fusible portion.

13. In a ventilating cover for a roof aperture, a cover element disposed in spaced relation above and overhanging the aperture,

an inclined wind baffle rising from the roof in spaced relation with the adjacent edge of the aperture and rising to a point beyond a plane connecting the adjacent edges of the 5 aperture and cover, the lower edge of said baffle having raised portions to provide water outlets between it and the roof, and means on the opposite side of the aperture from said baffle to deflect wind over said

10 cover.

14. A ventilating means according to claim 13, in combination with brackets mounted on the roof and adapted to brace the baffle and cover, and attaching means for 15 said brackets which fasten to the under side of the roof.

15. A ventilating cover for a roof aperture comprising an inner baffle disposed above the aperture and adapted to prevent 20 rain falling vertically into the aperture, and an outer baffle means rising to a level above

the adjacent side edge of the inner baffle and disposed and adapted to prevent rain being driven at an incline under said inner baffle into said aperture and to deflect wind 25 currents from flowing freely under the inner baffle into the ventilator, there being restricted outlets suitable for the escape of water falling between the baffles.

16. A protector for a roof ventilating 30 opening, comprising an inner baffle overhanging the opening and adapted to prevent rain falling vertically thereinto, and lateral outer baffles rising from the roof and spaced from the inner baffle and roof opening and 35 disposed to prevent rain falling at an incline into said opening, there being restricted water escape ports at the base of the outer baffles adapted to carry off rain falling between them.

40 In testimony whereof I affix my signature.

MacDOUGALD DEXTER.
